TIE FORM

Roland Seegmueller, San Pedro, Calif.

Application June 25, 1945, Serial No. 601,486

5 Claims. (Cl. 223—82)

1

This invention has to do with a tie form and it is a general object of the present invention to provide a device applicable to an ordinary four-in-hand necktie when it is not in use, to shape the tie ready for subsequent use in a manner so that the tie has the appearance of having been pressed.

Four-in-hand neckties as commonly worn by men are substantially uniform in size and shape and are almost invariably formed so that their end portions are open or unattached where they fold over to the inner side of the tie, forming what are commonly referred to as apron portions of the tie. Tapered flat tie stretchers are forming devices have been heretofore proposed and used and are often used while ties are being pressed. However, such devices are not satisfactory as structures on which ties can be left to stretch or be formed, in that the apron portions which are free will not stretch tightly on them but rather tend to spread and be loose, thus affecting the general shape of the tie.

It is a general object of my present invention to provide a tie form which can be applied to and left on a tie so that the entire large or front portion of the tie is effectively stretched or formed, giving it the appearance of having been pressed. By my present invention I not only stretch or effectively form the narrower portions of the tie where the tie is joined to be tubular, but I also effectively form or stretch the apron or end portion which is loose.

Another object of my invention is to provide a device of the general character hereinabove referred to which involves but two simple elements or sections that are simple and inexpensive of manufacture and simple and convenient to use.

It is another object of my invention to provide a device of the general character referred to wherein there is an outer section or retainer which effectively holds the apron portion of the tie and which can be applied so that it is frictionally held in place or which can be simply loosely slid in place to act by gravity to effectively hold the tie.

The various objects and features of my invention will be fully understood from the following detailed description of a typical preferred form and application of my invention, through-

2

out which description reference is made to the accompanying drawings, in which:

Fig. 1 is a view of a typical four-in-hand necktie showing the device of the present invention in place in connection therewith to form the large or front end of the tie. Fig. 2 is a view of the lower portion of the large end of the tie with the device in place taken from the rear side thereof. Fig. 3 is a face or plan view of the inner section of the device shown alone. Fig. 4 is an end elevation of the section shown in Fig. 3, being a view taken as indicated by line 4—4 on Fig. 3. Fig. 5 is a face or front elevation of the outer section of the device shown alone. Fig. 6 is a back or rear elevation of the outer section. Fig. 7 is an end view of the outer section as shown in Figs. 5 and 6, and Fig. 8 is an enlarged detailed sectional view taken as indicated by line 8—8 on Fig. 1.

20 The device that I have provided is applicable to the ordinary four-in-hand necktie such as I have shown in the drawings. Such a necktie has what may be termed a large end A and a small or narrow end B. The usual tie has a narrow neck portion C joining the end portions A and B and it is tubular in form or of tubular construction throughout most of its length. The extreme outer end portion of the end A and the extreme outer end of the end B of the ordinary tie are not tubular, but rather are open and are commonly known as the apron portions of the tie. This open or apron construction will be seen in Figs. 1 and 2 of the drawings.

25 The construction that I have provided involves, generally, an inner or stretcher section 10 and an outer or retainer section 11. The stretcher section is adapted to be inserted in the tie, for instance in the large end A of the tie, in the manner indicated in dotted lines in Fig. 1,

30 while the outer or retainer section is adapted to be engaged or clamped over the apron portion of the large end of the tie, as clearly illustrated in Figs. 1, 2 and 8 of the drawings.

The inner section or stretcher 10 is preferably formed of a flat sheet of material to be a tapered elongate part corresponding in size and shape to the large end A of the ordinary necktie. The stretcher 10 corresponds in length to the part of the tie required to be stretched or pressed, and the stretcher is preferably made to completely fill the large end A of the tie. The upper or nar-

35 10 11 40 45 50

row end of the stretcher will ordinarily be of about the width of the neck band portion C of the tie and may be provided with a suitable opening 12 to facilitate hanging on a hook, or the like, when not in use. The lower or large end of the stretcher at its widest point is as wide as the apron of the tie end A and the large end of the stretcher is shaped the same as the end of the tie, that is, it has downwardly and inwardly converging end edges 13 which join to form a rather blunt point, as clearly shown in Fig. 3. The side edges 14 of the stretcher are preferably straight and smooth although in practice they may be given a slightly concave curvature, if desired.

The outer section or retainer 11 is designed to fit over or bear against the apron portion of a tie in which the stretcher is applied. The retainer involves a flat body 20 corresponding in size and shape to the outer side of the tie apron, and it includes gripping jaws 21 adapted to engage around the edge portions of the tie apron to bear against the tie at the rear thereof. In practice I prefer to form the retainer 11 of sheet metal and to form the gripping jaws so that they define a space to slidably receive the tie carried on the stretcher A engaging the material of the tie at opposite points at the front and rear sides of the stretcher with sufficient friction to prevent slippage of the tie around the edge of the stretcher. In the preferred construction I provide a plurality of gripping jaws 21 along each edge of the body 20 in a manner such as I have shown in Figs. 5 and 6 of the drawings. The lower end of the retainer is shaped like the lower end of the stretcher, that is, it has downwardly and inwardly converging edges 22 which define a blunt point corresponding, generally, with the pointed end of a tie. In practice, I may provide the body 20 of the retainer with a suitable aperture 23 like the aperture 12 to facilitate hanging the retainer on a hook, or the like, when not in use.

In practice I prefer to form the stretcher 10 of a sheet of material such as a sheet of metal or of plastic, and as I have stated, I prefer to form the retainer 11 of sheet metal. The various corners and edges of both elements are finished to be smooth, so they will not mar or injure fabric. In using the device the tie after it has been used has the stretcher 10 inserted into the large end A, as indicated in the drawings. The retainer 11 is then placed over the face or front of the tie, which is located on the stretcher, at a point removed from the lower end of the tie far enough to allow the jaws 21 at opposite edges of the body 20 to be engaged over the edge portions of the tie. The retainer is then lowered or moved outward toward the apron of the large end A of the tie, until it reaches a position such as is shown in the drawings where the jaws 21 effectively engage and clamp the apron portion of the tie to the stretcher 10. The tie can then be suspended or hung by any suitable means such as a simple clamp or clasp in a position such as is shown in Fig. 1, so that gravity acting on the retainer tends to clamp it firmly in position, or the retainer can be slid into a tight position over the spreader and the tie allowed to rest in a horizontal position. In the latter case it is preferred to have the stretcher placed snugly in the tie in order to give the desired stretching action.

When using the device that I have provided as above described the fabric of the tie will be effectively stretched or formed over the stretcher and the retainer will effectively hold the apron portion of the tie in position on or over the

stretcher, so that the entire front or large end A of the tie is effectively and uniformly stretched, giving it the appearance of being a new or freshly pressed tie. It is to be observed that the device is extremely simple of manufacture, in that it involves but two simple, inexpensive parts or sections, and it is also to be noted that the parts are very simple and convenient to manipulate both to apply to a tie and to remove from a tie, making the device practical for general use.

Having described only a typical preferred form and application of my invention, I do not wish to be limited or restricted to the specific details herein set forth, but wish to reserve to myself any variations or modifications that may appear to those skilled in the art and fall within the scope of the following claims.

Having described my invention, I claim:

1. A device for application to a necktie including, an elongate flat longitudinally tapered stretcher insertable into the tie from one end, and a retainer applicable to an end portion of the tie on the stretcher to cooperate with the stretcher in holding the tie and confining the end portion thereof to the stretcher, the stretcher being of fixed size and shape corresponding in size and shape to the said end of the tie and the retainer being freely movable lengthwise of the stretcher and cooperating with the stretcher to move toward the large end of the stretcher and clamp a tie to the stretcher under the influence of gravity when the stretcher is vertically disposed with its large end lowermost.
2. A device for application to a necktie including, a stretcher plate of fixed size and shape insertable into the tie from one end, and a retainer applicable to an end portion of the tie to cooperate with the stretcher in holding the tie and confining the end portion thereof to the stretcher, the retainer including a flat body to bear on the front of the end portion of the tie, and jaws at the edges of the body engageable over the edge portions of the tie and bearing on the back of the tie.
3. A device for application to a necktie including, a stretcher plate of fixed size and shape insertable into the tie from one end, and a retainer applicable to an end portion of the tie to cooperate with the stretcher in holding the tie and confining the end portion thereof to the stretcher, the retainer including a flat body with a smooth uninterrupted inner face to bear on the front of the end portion of the tie and shaped to substantially correspond to the end portion of the tie, and jaws at the edges of the body engageable over the edge portions of the tie and bearing on the back of the tie.
4. A device for application to a necktie including, an elongate longitudinally tapered stretcher plate insertable into the tie from one end, and a retainer plate applicable to an end portion of the tie to cooperate with the stretcher in holding the tie and confining the end portion thereof to the stretcher, the retainer and the outer end portion of the stretcher being of fixed size and shape and corresponding substantially to the size and shape of the outer end portion of said tie end and the retainer being freely movable lengthwise of the stretcher and being wedged thereon holding the tie on the stretcher when the stretcher is vertically disposed with the small end up, there being mounting means for the device at the small end of the stretcher.
5. A device for application to a necktie including, an elongate stretcher plate of fixed size

and shape insertable into the tie from one end and having its side edges pitched so it is tapered to correspond in shape to the said end of the tie, and a rigid retainer applicable to the end portion of the tie to cooperate with the stretcher in holding the tie and confining the end portion thereof to the stretcher, the side edges of the retainer being pitched the same as the side edges of the stretcher and having jaws projecting transversely of the stretcher and engageable over the edges of the stretcher to confine the retainer to the portion of the tie on the stretcher.
